LATCH

Charles Ledin, Stamford, Conn., assignor to The
Yale & Towne Manufacturing Company, Stamford,
Conn., a corporation of Connecticut

Application April 25, 1944, Serial No. 532,583

15 Claims. (Cl. 292—228)

1

This invention relates to a latch for a door, as for example, a screen door. It is an object of the invention to contribute a latch that is extremely simple to apply to a door, that is adapted for easy and enduring operation, that presents a pleasing appearance, and is inexpensive and easy to manufacture.

A feature of my invention whereby the above objectives are obtained resides in the utilization of a novel form of latch adapted for operation by a handle member. More particularly, this feature of my invention resides in a pivoted handle structure with which is associated a pivoted latch bolt, the latch bolt being pivoted preferably on the handle outwardly from the door and extending toward the door with its latching surface between the door and its pivot. This arrangement of the latch bolt contributes an extremely easy operating mechanism as those skilled in the art will readily recognize.

A still further feature of my invention resides in the construction of the latch bolt, it being preferably of channel form with the handle positioned between the flanges of the channel so that the latch bolt overlies and encompasses the handle. A still further feature of this portion of my invention resides in the means utilized for limiting the pivotal movement of the latch bolt relatively to the operating handle on which it is pivoted.

A still further feature of my invention resides in the dogging mechanism utilized for dogging the operating handle of my latch.

I have thus outlined the more important features of my invention in order that my contribution to the art may be better understood and in order that the relation of my contribution to the prior art may be better comprehended. I do believe that my contribution is broad and that I am entitled to patent claims not limited to the structural details of my invention hereinafter set forth. Also, while I have described generally several important features of my invention, there are other important features that will be described particularly in the specification and will be claimed in the claims appended hereto.

Referring now to the drawings, Fig. 1 is a perspective view of the latch applied to a door. Fig. 2 is a perspective view showing the side of the door opposite that of Fig. 1. Fig. 3 is a horizontal section through the latch and door showing particularly the cooperation of the latch bolt and the strike. Fig. 4 is a section through Fig. 3 taken substantially along lines 4—4 of Fig. 3. Fig. 5 is a view similar to Fig. 3 showing the dogging member in released position and the latch

2

bolt held retracted by the operating handle. Fig. 6 is a section taken along 6—6 of Fig. 4. Fig. 7 is a section taken along lines 7—7 of Fig. 6.

Referring now more particularly to the drawings, my latch comprises an inner mounting plate 10 best illustrated in Figs. 1, 3 and 5 and an outer escutcheon 11 best illustrated in Fig. 2. Mounting plate 10 is formed with a pair of inwardly extending ears 12 that are best illustrated in Figs. 3 and 4, these ears being adapted for insertion into a bore B that is formed in the door 13 to which my latch is to be applied. The ears 12 are bored for the mounting therein of a shaft 14 and a pin 15. Rotatable about the shaft 14 is a handle or latch operator designated generally by reference numeral 16. This handle 16 is preferably formed by me of one piece, and it may be a die casting or of sheet metal or any other construction that may be found desirable from time to time. A spring 17 is mounted about the shaft 14 and extends over the pin 15 at one end while bearing against a lug 18 of the handle 16 at its other end. It is of course the function of the spring 17 to rotate the handle 16 clockwise in Fig. 3 to bring its limit shoulder 19 against the mounting plate 10, all as is quite apparent.

The jamb with which the door 13 cooperates is designated by reference numeral 20 and has mounted thereon a strike 21. Cooperating with this strike 21 is a latch bolt 22 that is best shown in perspective in Fig. 1. The latch bolt 22 is channel in form, and is adapted to fit over the shank of the handle 16 with the shank of the handle 16 lying between the flanges 22a of the latch bolt 22. The flanges of the latch bolt are drawn or otherwise suitably formed as shown at 23 in Fig. 7 to furnish bearing surfaces for cooperation with spring pressed pins 24 urged by a spring 25 against the said bearing surfaces. Those skilled in the art will readily appreciate that it is the function of the pins 24 to mount the latch bolt 22 for pivotal movement relatively to the handle 16.

For limiting this pivotal movement, the latch bolt 22 is formed with a depression 26 for cooperation with the head 27 of a threaded pin 28 having a threaded limit sleeve 29 mounted thereon, all as shown in Figs. 6 and 7. The threaded pin 28 extends through an opening 30 in the latch bolt depression 26 and into a bore 31 of the handle 16. It passes also through an opening 32 in a limit plate 33 secured relatively to the bore 31 of the handle 16. The end of the limit sleeve 29 fits against the limit plate 33 and serves to limit movement of the pin 28 to the left from

its position of Fig. 6. A spring 35 passes through a bore 36 in the pin 28 and is formed with a leg 37 lying against a surface of the handle 16. It is of course the function of the spring 35 to urge the latch bolt counter-clockwise about the pivot pins 24 in Figs. 3, 5 and 6, and with the threaded pin 28 and sleeve 29 limiting this movement. As is quite apparent from the drawings, rotation of the sleeve 29 as by a screw driver will adjust the possible throw of the latch bolt by the spring 35. Through the utilization of the mechanism illustrated in Figs. 6 and 7, I obtain a very simple and effective latch adjusting mechanism for adjusting the throw of the latch bolt 22.

Those skilled in the art will now appreciate that the latch bolt 22 is adapted for cooperation with the strike 21 as illustrated in Fig. 3 to prevent opening movement of the door. When the handle or operating member 16 is not dogged by means to be described presently, it may be rotated counter-clockwise from its position of Fig. 3 to its position of Fig. 5. This rotation naturally withdraws the latch bolt 22 from locking position, and the door may be opened. If the door is open and the latch bolt 22 and handle 16 are in their positions of Figs. 1 and 3, the latch bolt will impinge against the strike 21 as the door moves into closing position. The strike will readily overcome the resistance of the spring 35, and will cam the latch bolt 22 so that it will pivot clockwise from its position of Figs. 3 and 6 until the door reaches its position of Fig. 3. The latch bolt 22 will then be spring pressed outwardly into its locking position of Fig. 3 as is well illustrated.

It is interesting to note that in Fig. 3 the surface 22b of the latch bolt, called by me the latching surface, is adapted to be maintained in locking relation to the strike 21 even were the door to move even further toward closing position. Therefore, the latch bolt surface 22b is in a position to absorb any wear that may occur in the parts, or to compensate for warping or other displacement of the door.

For dogging the handle 16 against movement from the position of Fig. 3 to the position of Fig. 5, I utilize a dog designated by reference numeral 40 and having a detent 41 adapted to enter a slot 42 in the mounting plate 10 defined at one end by a shoulder 43. Dog 40 is shown in Fig. 3 pressed by a spring 44, into its dogging position, in which position it blocks counter-clockwise rotation of handle 16 as is apparent. In order to move the dog 40 into its release position of Fig. 5, it is necessary to depress it through pressure on the manually operated pin 45, moving the detent 41 out of the slot 42. Thereafter, the dog may be moved to its position of Fig. 5 and out of dogging position. To move the dog 40 back into dogging position, it need only be moved to the left in Fig. 5. The spring 44 will force the detent 41 into the slot 42 as soon as the detent is in position to enter the said slot. I believe that the operation and construction of the dogging mechanism will now be apparent.

It will be noted from Figs. 2, 3 and 4 that the escutcheon 11 is slotted as at 50 to permit movement of the handle 16 from its position of Figs. 1 and 3 to its position of Fig. 5. It is highly desirable that the slot 50 be closed against access in all positions of the handle 16. For the particular purpose, the handle 16 is slotted as at 51 and 52, and for entering the said slots 51 and 52, I utilize a plate 53. This plate 53 is formed with a pair of legs 54 that are adapted to be slipped over the handle 16 and through the slots 51. The plate

53 is preferably formed of metal that is spring-like in character and capable of allowing the spreading of legs 54 as those legs move into the position of Fig. 4 into the slots 51 and 52. The plate 53 will be retained because of its spring-like nature in its position of Figs. 2 and 4 and will effectively block the slot 50, as is probably best illustrated in Fig. 2.

I believe that the operation and construction 10 of my invention will now be apparent to those skilled in the art.

I now claim:

1. In a latch of the class described, a mounting member adapted to be applied to a door, a handle 15 pivotally mounted on said mounting member and having hand grips adapted to extend outwardly at each side of the door whereby said handle may be swung on its pivot axis, a latch bolt pivoted on said handle at a pivot point displaced outwardly from the door and from the pivot axis of said handle, and extending from said pivot point toward said door, a latching surface formed on the portion of said latch bolt between the door and said pivot point about which it is pivoted relatively to said handle, and spring means for pressing the latch bolt to latching position about its pivot.
2. In a latch of the class described, a mounting member adapted to be applied to a door, a handle 30 pivotally mounted on said mounting member and having a hand grip adapted to extend outwardly at one side of the door whereby said handle may be swung on its pivot axis, a latch bolt pivoted on said handle at a pivot point displaced outwardly from the door and from the pivot axis of said handle, and extending from said pivot point toward said door, and a latching surface formed on the portion of said latch bolt between the door and its pivot.
3. In a latch of the class described, a mounting member adapted to be applied to the face of a door, a handle pivotally mounted on said mounting member and having a pair of hand grips, one of said hand grips extending from said mounting member through an opening of the door to be accessible at one side of the door, while the other hand grip is accessible at the side of the door to which said mounting member is applied, a latch bolt pivoted on said handle at a pivot point displaced outwardly from the door and from the pivot axis of said handle, and extending from said pivot point toward said door, a latching surface formed on the portion of said latch bolt between the door and said pivot point, and spring means for pressing said latch bolt to latching position about its pivot.
4. In a latch of the class described, a mounting member adapted to be applied to a door, a handle 60 pivotally mounted on said mounting member and having hand grips adapted to extend outwardly at each side of the door whereby said handle may be swung on its pivot, a latch bolt pivoted on said handle at a point displaced outwardly from the door and from the pivot axis of said handle, and extending from said pivot point toward said door, a latching surface formed on said latch bolt between the door and said pivot point, a spring moving said handle and latch bolt toward latching position, said latch bolt being movable with said handle to non-latching position against said spring, and being movable also on its pivotal mounting relatively to said handle into non-latching position.
5. In a latch of the class described, a mounting 75 member adapted to be applied to the face of a

door, a handle pivotally mounted on said mounting member and having a pair of hand grips, one of said hand grips extending from said mounting member through an opening of the door to be accessible at one side of the door, while the other hand grip is accessible at the side of the door to which said mounting member is applied, a latch bolt pivoted on said handle at a point displaced outwardly from the door and from the pivot axis of said handle, and extending from said pivot point toward said door, a latching surface formed on said latch bolt between the door and said pivot point, a spring for pressing said latch bolt to latching position about its pivot, a second spring moving said handle and latch bolt toward latching position, said latch bolt being movable with said handle to non-latching position against said second spring and being movable also on its pivotal mounting against said first spring and relatively to said handle into non-latching position.

6. In a latch of the class described, a mounting member adapted to be applied to a door, a handle pivotally mounted on said mounting member and having hand grips adapted to extend outwardly at each side of the door whereby said handle may be swung on its pivot, a channel shaped latch bolt pivoted on said handle at a point displaced outwardly from said door and with the handle lying between the flanges of the U formed by the channel, said latch bolt extending from said pivot point toward said door, a latching surface formed on said latch bolt between the door and said pivot point, and spring means for pressing said latch bolt to latching position about its said pivot.

7. In a latch of the class described, a mounting member adapted to be applied to a door, a handle pivotally mounted on said mounting member and having a hand grip adapted to extend outwardly at one side of the door whereby said handle may be swung on its pivot, a channel shaped latch bolt pivoted on said handle at a point displaced outwardly from said door and with the handle lying between the flanges of the U formed by the channel, said latch bolt extending from said pivot point toward said door, and a latching surface formed on said latch bolt between the door and said pivot point.

8. In a latch of the class described, a mounting member adapted to be applied to a door, a handle pivotally mounted on said mounting member and having hand grips adapted to extend outwardly at each side of the door whereby said handle may be swung on its pivot, a channel shaped latch bolt pivoted on said handle at a point displaced outwardly from said door and with the handle lying between the flanges of the U formed by the channel, said latch bolt extending from said pivot point toward said door, a latching surface formed on said latch bolt between the door and said pivot point, spring means for pressing said latch bolt to latching position about said pivot, a spring moving said handle and latch bolt together toward latching position, said latch bolt being movable with said handle to non-latching position against said spring and being movable also on its pivotal mounting against said spring means and relatively to said handle into non-latching position.

9. In a latch of the class described, a mounting member adapted to be applied to a door, a handle pivotally mounted on said mounting member and having a hand grip adapted to extend outwardly at one side of the door whereby said handle may be swung on its pivot, a latch bolt pivoted on said handle at a point displaced out-

wardly from the door and extending from said pivot point toward said door, a latching surface formed on said latch bolt between the door and said pivot point, spring means pressing said latch bolt to latching position about said pivot, and means for adjusting the length of movement of said latch bolt relatively to said handle by said spring means.

10. In a latch of the class described, a mounting member adapted to be applied to a door, a handle pivotally mounted on said mounting member and having a hand grip adapted to extend outwardly at one side of the door whereby said handle may be swung on its pivot, a latch bolt pivoted on said handle at a point displaced outwardly from the door and extending from said pivot point toward said door, a latching surface formed on said latch bolt between the door and said pivot point, spring means pressing said latch bolt to latching position about said pivot, and threaded means extending between said latch bolt and handle for limiting the movement of said latch bolt relatively to said handle by said spring means.

11. In a latch of the class described, a latch operator, means mounting said operator for pivotal movement, a spring pressing said latch operator toward a latching position, a channel shaped latch bolt, means mounting said latch bolt for pivotal movement on said latch operator and with said latch operator positioned between the flanges of the U formed by said channel, said latch bolt being movable bodily with said latch operator as said latch operator pivots on its mounting means, and a spring positioned between said latch operator and latch bolt for pressing said latch bolt to latching position relatively to said latch operator.

12. In a latch of the class described, a mounting member, a latch operator movable relatively to said mounting member, a dog mounted for movement on said mounting member into a dogging and a non-dogging position relatively to said latch operator, portions of said mounting member and dog coacting for locking said dog against movement from dogging to non-dogging position when pressure is applied by said latch operator against said dog, spring means yieldingly maintaining said dog and mounting member portions in position for coacting, said spring means being adapted for manual actuation whereby said portions are withdrawn from coaction and said dog is movable to non-dogging position.

13. In a latch of the class described, a mounting member, a latch operator movable relatively to said mounting member, a dog mounted for sliding movement on said mounting member into a dogging and a non-dogging position relatively to said latch operator, portions of said mounting member and dog coacting for locking said dog against sliding movement from dogging to non-dogging position when pressure is applied by said latch operator against said dog, a spring pressing said dog against said mounting member to maintain said portions in coacting and locking relation, said dog being movable manually against the pressure of said spring to withdraw said portions from coaction and to release said dog for movement to non-dogging position.

14. In a latch of the class described, a latch operator, means mounting said operator for movement, a channel shaped latch bolt, and means mounting said latch bolt for pivotal movement on said latch operator and with the outer opposed surfaces of said latch operator positioned between

and in juxtaposed relation to the flanges of the U formed by said channel.

15. In a latch of the class described, a latch operator, means mounting said operator for movement, a channel shaped latch bolt, opposed spring pressed bearing members mounted in a bore of said operator and entering opposed bearings on the inside surfaces of the flanges of said channel shaped latch bolt for mounting said latch bolt for pivotal movement on said latch operator, said latch operator being positioned between the flanges of the U formed by said channel and with the outer opposed surfaces of said latch operator lying juxtaposed to the flanges of said latch bolt in reinforcing relation thereto.

15
